(Cl. D64—11)

To all whom it may concern:

Be it known that I, George R. Munsie, a citizen of the United States, residing at Stamford, in the county of Fairfield and State of Connecticut, have invented a new, original, and ornamental Design for a Combined Stacking Device and Stand, of which the following is a specification, reference being had to the accompanying drawing, forming part thereof, wherein:

Fig. 1 is a front perspective view of a combined stacking device and stand showing my new design;

Fig. 2 is a side elevational view thereof looking at the left end of Fig. 1; and,

Fig. 3 is a top plan view thereof.

I claim:

The ornamental design for a combined stack-
ing device and stand, substantially as shown.

GEORGE R. MUNSIE.
